UNITED STATES PATENT OFFICE

HARRY W. PROTZELLER, OF EAST CHICAGO, INDIANA, ASSIGNOR TO O. F. JORDAN COMPANY, OF EAST CHICAGO, INDIANA, A CORPORATION OF INDIANA

RAILROAD WAY CONSTRUCTION AND MAINTENANCE CAR

Application filed April 22, 1929. Serial No. 356,916.

This invention relates to improvements in railroad way construction and maintenance cars and it consists of the matters herein-after described and more particularly pointed out in the appended claims.

In cars of this kind which include an inner spreader and ballast wing and an outer material carrying and bank shaping wing, the outer wing was only capable of being 10 swung upwardly by power means, in the plane of the inner wing and could only swing downwardly in changing the angular position thereof, under the action of gravity, due to the weight of the wing. As the 15 downward movement was only actuated by the weight of the outer wing, the working depth was limited and when working in certain materials, this caused extra operations and movements of the car to get down 20 to depth or cut desired.

The primary object of the invention is to provide an improved operating means for exerting a positive upward pull or a positive downward push on the outer wing to 25 swing it into the desired angular relation with respect to the inner wing.

A further object of the invention is to provide a construction of this kind which is positive in operation and includes a positively actuated, reciprocable cross-head on 30 the top edge of the inner wing, with a rigid link or member between said cross-head and the outer wing for swinging the outer wing into the desired position, which link is readily disconnectible from the outer wing when 35 it is desired to swing the same into material carrying position with respect to the inner wing.

These objects of the invention, as well as 40 others together with the many advantages thereof, will more fully appear as I proceed with my specification.

In the drawings:

Fig. 1 is a view in side elevation of one 45 end of a railroad way construction and maintenance car embodying my improved construction and shows the inner and outer wings at one side of the car as when swung inwardly toward the car.

Fig. 2 is a transverse vertical detail sec-

tional view on an enlarged scale through a part of the same as taken on the line 2-2 of Fig. 1.

Fig. 3 is a horizontal detail sectional view also on an enlarged scale as taken on the line 3-3 of Fig. 1.

Referring now in detail to that embodiment of the invention illustrated in the accompanying drawings, 1 indicates as a whole, the body of the car provided at both ends with wheels 2 for travel upon the rails of a railroad track 3. At the front end of the car is a V-shaped front plow 4 and at each side of the car, to the rear of said plow, is a plow wing 5. Said plow and its side wings are vertically adjustable by means of an upright pneumatic cylinder 6 disposed at the front end of the car body.

Rising from each side of the car body and its underframing, at substantially the rear end of the plow wings 5-5, is an upright wing post 7 and above the decking of the body to the rear of the post is the operator's cab 8. The top end of each wing post is braced by bars 9 from an associated standard 10 rising from the body just to the rear of the front plow 4.

Mounted on the bottom portion of the wing post for a vertical as well as a turning movement, is a hinge plate 11 and on the top portion of said post is a collar 12 also mounted for a vertical and a turning movement. 13 indicates a horizontally disposed boom fixed at its inner end to the collar 12 and the outer end of said boom is secured to the top end of a brace 13^a, the lower end of which is fixed to said hinge plate.

14 indicates the inner spreader or ballast wing, there being one of such wings associated with each wing post. Said inner wing comprises a casting like body 15 and a front plate 16 and the inner end of said wing is embraced by the hinge plate and is pivoted thereto as at 17 for a swinging movement about a horizontal axis. Such swinging movement is imparted to said wing by means of a double acting power cylinder 18 pivoted at its top end to the junction of the boom 13 and its brace 13^a.

To the other end of said cylinder is secured a yoke 19 including a tubular body 20. Telescopically slideable in said body is a tube or rod 21, the top end of which is operatively connected to the piston in the cylinder 18 while the bottom end of said tube or rod is pivoted upon a cross-pin 22 mounted in the top ends of front and rear bearing plates 23 and 24, respectively, on the wing 14 near its outer end.

When air under pressure is admitted to one end or the other of the cylinder 18, the tube 21 telescopes inwardly or outwardly of the body 20 so as to impart a raising or lowering swinging movement to the wing 14 about its pivotal connection 17 with the hinge plate. On the body 20 is a suitable locking device 25 by which the tube or rod is locked to the body 20 to hold the wing in the desired angular position. Suitable means, not herein shown, operatively connect the body 1 of the car with the rear side of the wing 14 whereby said wing may be swung about the wing post away from or toward the car body. On the bottom edge of the outer end of the wing 14 is a ditching blade 26 by which a ditch may be formed when the car is used for its intended purpose.

27 indicates the outer or bank shaping and material carrying wing. Said wing, which is normally disposed in the plane of the wing 14, is pivoted at its front end as at 28 to a substantially segmental shaped plate 29 which in turn is pivoted on a horizontal pivot 30 to the bottom outer corner of the front face of the inner wing 14. The arcuate marginal portion of said plate extends under an arcuate guide strip or flange 31 having holes 32 therein and a locking pin 33 may be inserted through the desired hole 32 and through a hole in the segmental plate 29 to lock said plate to the inner wing in any one of several different angular positions.

40 To swing the outer wing, either upwardly or downwardly about the horizontal pivot 30, I provide the following positive construction. 34 indicates a double acting pneumatic cylinder supported upon the top edge of the inner wing, near its inner end. In said cylinder is the usual piston having a rod 35 that slides through a stuffing box at the outer end of said cylinder. On the top edge of the outer end of said wing 14 is fixed a chan-

nel 36 with its flanges directed upwardly and secured to said channel is an I-beam like guide 37 with its web disposed vertically. 38 indicates a cross-head having a hook like guided sliding movement on the top flanges of said I-beam and to one end of said cross-head is fixed the outer end of the piston rod 35 associated with the cylinder 34.

39 indicates a bracket like casting secured to the rear side of the outer wing near its

top, at a point spaced a suitable distance from the inner end thereof. This bracket includes laterally spaced ears 40—40 to which may be removably but pivotally connected the outer end of a rigid link 41 by means of a pin 42. The other or inner end of said rigid link is pivotally connected to the outer end of the cross-head as by a pin 43.

When the outer wing is disposed in the plane of the inner wing so as to form an extension therefor and it is desired to change the relative angular position of the outer wing with respect to the inner wing, the pin 33 is first withdrawn to unlock the two wings. Should it be desired to raise or swing the outer wing into the dotted line position shown in Fig. 1, air is admitted to the outer end of the cylinder 34 so that the piston therein is forced toward the inner end of said cylinder. This causes the cross-head 38 to move inwardly on its guide 37 and through the link 41 and pin 42 will exert an upward pull to swing the outer wing upwardly about the pivot 30. The locking pin 33 is replaced to hold the outer wing in the desired angular position with respect to the inner wing.

When it is desired to swing the outer wing downwardly, the locking pin 33 is withdrawn and air under pressure is admitted to the inner end of the cylinder whereby the piston therein and its rod is forced outwardly and this pushes the cross-head 38 positively outward on its guide beam 37. As the link 41, which is a rigid member, connects the cross-head and bracket 39 on the outer wing, said outer wing is swung downwardly about its pivot 30.

When it is desired to employ the outer wing 27 as a material carrying wing, the pin 42 is withdrawn and the usual braces (not shown) for connecting said wing with the car are disconnected after which the inner wing 14 is swung outwardly to the desired position. Then the outer wing is swung outwardly and forwardly so that its outer end may be engaged by a brace 44 swingable on the post 10 so as to hold said wing in its material carrying position.

From the above, it is apparent that when the outer wing is in a position forming an extension or continuation of the inner wing, said outer wing may be positively swung up or down about the pivot 30 into the desired position.

It is, of course, understood that suitable conduits for air under pressure lead from the cylinders 18 and 34 to a suitable source of supply, which is controlled by valves positioned in the cab convenient for the operator.

The construction above described is simple and of great strength and is indeed posi-

tive and efficient in operation for its intended purpose.

While in describing my invention, I have referred in detail to the form, arrangement, 5 and construction of the various parts thereof, the same is to be considered merely as illustrative so that I do not wish to be limited thereto except as may be pointed out in the appended claims.

10 I claim as my invention:

1. The improvement herein described comprising in combination with a car, a wing pivotally connected at one end to the car, a second wing pivotally connected to 15 the first wing for a swinging movement about a horizontal axis, a power device on the first wing and including a rod positively movable endwise in either direction and a rigid member having a pivotal connection at one end with the free end of said rod and having a pivotal connection at its other end with the rear side of said second wing near its top edge.

2. The improvement herein described comprising in combination with a car, a wing pivotally connected at one end to the car, a second wing pivotally connected to the first wing for a swinging movement about a horizontal axis, a power cylinder including 30 a rod positively movable endwise in either direction, a cross-head having a guided movement on said wing and operatively connected to the rod and a rigid link having a pivotal connection at one end with said 35 cross-head and having a pivotal connection at its other end with the rear side of said second wing near its top edge.

3. The improvement herein described comprising in combination with a car, a wing pivotally connected at one end to the car, a second wing pivoted at one end to the first wing for a swinging movement about a horizontal axis, means providing a guide along the top edge of the first wing, 45 a cross-head slidable thereon for a guided movement, power means on said first wing for positively moving the cross-head on said guide means in either direction and a rigid member pivotally connected at one end to 50 said cross-head and having a pivotal connection at its other end with the rear side of said second wing near its top edge.

4. The improvement herein described comprising in combination with a car, a wing pivotally connected at one end to the car, a second wing pivoted at one end to the first wing for a swinging movement about a horizontal axis, an I-beam guide on the top edge of the first wing, a cross-head having a sliding guiding movement on said guide, power actuated means carried on the wing and operatively connected with the cross-head for moving the same positively in either direction on the guide and a rigid 60 member pivotally connected at one end to 65

said cross-head and having a pivotal connection at its other end with the rear side of said second wing near its top edge.

In testimony whereof, I have hereunto set my hand, this 18th day of April, 1929.
